PACKAGED DOOR UNIT

Glenn I. Logue, Jacksonville, Fla., assignor to Con-Dor Corporation of America, Jacksonville, Fla., a corporation of Florida

Application August 19, 1952, Serial No. 305,116

9 Claims. (Cl. 20—12)

This invention relates to prefabricated door and door frame units and more particularly to such units of the split-jamb type.

The hanging of doors and the trimming out of the frames has always been an expensive and time-consuming task. Even though prefabricated door and frame units are known, considerable trouble has been encountered in setting up the units, getting them properly plumbed in the rough frame studding and aligning the separate sections of the jamb before permanently securing them in place. Many on-the-job improvisations have been resorted to to hold the various parts in position while they were being aligned and permanently fastened. Many times the jambs were warped during installation so that the frame was not plumb and an imperfectly operating door resulted.

The object of the present invention is to provide a prefabricated door and frame incorporating means for initially plumbing the first section of the two-part frame and holding it in adjusted position while the remaining portion is installed.

Another object of the invention is to provide in such structure means for accurately aligning the two sections and holding them properly aligned while they are being permanently fixed to the studding.

A further object of the invention is to provide aligning means for the sections which also forms a solid base to hold the jambs against warping as they are being secured in position.

A still further object is the provision of means for initially plumbing the first section to be installed, which means also serves as aligning means for the several sections.

Other objects of the invention will become apparent from the following description of practical embodiments thereof when taken in conjunction with the drawings which accompany, and form a part of, this specification.

In the drawings:

Figure 1 is an elevational view of a door and frame structure, embodying the principles of the present invention, shown installed;

Figure 2 is a vertical section taken on the line 2—2 of Figure 1;

Figure 3 is a horizontal section through one of the jambs showing the means for initially plumbing the unit, and is taken on the line 3—3 of Figure 2;

Figure 4 is a perspective view of one of the jacks used for initially plumbing the unit and for aligning the sections of the unit;

Figure 5 is a fragmentary elevational view showing a portion of one of the jambs and illustrating a slightly modified form of the invention; and,

Figure 6 is a partial horizontal section through the structure shown in Figure 5, and is taken substantially on the line 6—6 of Figure 5.

In general, the present invention comprises a prefabricated door and frame assembly of the two-part jamb

2

type having means for initially holding the frame in place in the rough studding framing the door opening, which means also serves to align the sections of the jambs and form a solid base to hold the jamb sections in position while nailing or screwing the assembly in place.

Referring to the drawings in detail, there is shown the customary rough framing in a partition wall 1 outlining the door opening and to receive the door and door frame. The framing consists of the usual vertical studding members 2 which are spaced apart a distance greater than the desired width of the finished door opening, and the horizontal member 3 bridging the tops of the vertical members 2. The prefabricated door frame of the present invention is split longitudinally into what will be referred to as a front section 4 and a back section 5. The two sections are put in place from opposite sides of the door opening to form the finished frame. The front section 4 of the frame consists of the two jambs 6 and 7 and the lintel 8. The jambs 6 and 7 are permanently fixed to the lintel 8, and held in spaced parallel relation by means of the lintel. The usual facing panels 9, 10 and 11 are nailed to the jambs 6 and 7 and the lintel 8. These panels may be trimmed in any desired manner with moulding strips. When the frame is in place in the door opening the panels cover the rough studding. A door 12 is mounted in the front section of the frame by means of hinges 13 fixed to the jamb 6. The door has the usual provision for a latch and locking means to cooperate with the jamb 7.

The inner edge of each jamb is provided with arcuate recesses 14 spaced apart along its length. Three such recesses are shown on each jamb, but it will be understood that in actual practice more will be provided as required. They probably will be located on eighteen-inch centers. The lintel 8 has its rear edge similarly recessed, as shown at 15. Recesses 14 form the mounting means for small jacks 16. Jacks 16 have a cylindrical hub portion 17 which is of a length substantially equal to the thickness of the wood of the jambs. A flange 18, of considerably larger diameter than the hub, encircles the jack approximately at the center of the hub, and when the flange is seated in a recess 14, the ends of the hub are substantially flush with the side surfaces of the jamb. Hub 17 is centrally bored and screw-threaded to receive a screw 19 which carries a bearing head 20. The opposite end of the screw 19 has a kerf so that a screw driver may be used to move the bearing head toward and away from the hub portion of the jack. After the flange of the jack has been inserted in one of the recesses 14, a small nail 21 is driven through the jamb and passes through an opening 22 in the flange 18 of the jack to securely hold the jack in position upon the jamb.

No jacks are used along the lintel 8, but disks 23, similar to the flanges 18 of the jacks, are seated in the recesses 15 and held in place by nails 24. Disks 23 are imbedded in the lintels slightly less than half their diameters, as are the flanges 18 in the jambs, so that they project well beyond the rear edges of the lintel.

The back section of the frame is composed of the spaced jambs 25 and 26 and the lintel 27. Face panels 28, 29 and 30 are attached to the jambs 25, 26 and lintel 27 respectively. The jambs have arcuate recesses 31, similar to recesses 14 and similarly spaced along the rear edges of the jambs. Lintel 27 has the recesses 32. After the front section of the frame has been put in place, as will be described, the back section is slipped into the rough opening and the protruding portions of the flanges 18 of the jacks and the disks 23 fit into the respective recesses 31 and 32 of the back section. This

will bring the inner surfaces of the jambs and lintels of the two frame sections into absolute alignment. Any gap between the edges of the two frame sections will be covered by the installation of a conventional bumper strip 33.

In installing the prefabricated frame and door unit just described, the front section of the frame with the door in place is slipped into the roughed-in opening until the face panels 9, 10 and 11 lie flat against the plaster or other finishing substance on the wall. The jacks 16 will then be manipulated by means of a screw driver to bring the bearing heads 20 snugly up against the vertical studding members 2. These can be adjusted to set the frame and door plumb in the opening. The jacks are tightened sufficiently against the studding to hold the frame snugly in place. The sill 10' may be secured in place bridging the bottoms of the jambs of the front section to hold the jambs in proper spaced relation during shipping and to prevent the bottom of the jambs from being forced toward one another as the jacks are tightened against the studding. If desired, the sill may be omitted and any suitable brace (not shown) used in its place during shipping and installation. When the front section is firmly in place, the other section of the frame is slipped into the opening from the other side of the wall or partition. The recesses 31 and 32 are slipped onto the projecting portions of the flanges 18 and disks 23, and the back section pushed inwardly until the facing panels 28, 29 and 30 lie flush against the wall. The distance separating the edges of the sections when in place will vary according to the thickness of the wall. The jambs of the two sections can be nailed or otherwise secured to the studding to permanently hold the frame in place. The nails will be driven through the jambs close to the jacks 16 which will hold the jambs perfectly true during the nailing. The jacks, bearing against the studding, form rigid bases to prevent movement of the jambs as the nails are driven in. After the two frame sections are securely fastened, the bumper strip 33 is nailed in place covering the gap between the edges of the jamb and lintel sections. This completes the installation.

It will be understood that the two frame sections will be prefabricated and the door hung in the front section at a mill and the unit shipped to the job where it is to be installed. The unit will be suitably braced and packed for shipment to prevent damage.

In Figures 5 and 6 a slightly modified form of the invention is shown. Here, the jambs 34 of the front section are grooved, as at 35, along the entire length of their rear edges, and receive a tongue 36. The tongue is as long as the groove and may be fixed in the groove by brads 37, or by other means. The protruding portion of the tongue is provided with a plurality of openings 38 which are spaced along the tongue close to the edge of the jamb 34 to receive the hubs 39 of jacks 40. In this form, the jacks have flanges 41 at one end of the hub which are smaller than the flanges 18 of the form previously described. The flange fits against one side of the tongue 36 and may be riveted or otherwise secured to the tongue, as at 42. The hub is bored and tapped to receive the screw 43 having a bearing head 44. The inner edge of the rear jamb section 45 is also provided with a longitudinal groove 46 so that when the two sections of the frame are fitted together the tongue 36 will fit within the groove 46 to align the sections. It will be understood that the lintel sections may be provided with similar grooves and a tongue (not shown) for aligning these portions.

The modified structure is assembled in the same manner as that previously described. The front section is put in the opening and plumbed and locked in position by means of the jacks 40. The rear section is then put in place and the assembly permanently fixed in place.

While practical embodiments of the invention have been described above, it will be understood that the pre-

cise structure disclosed is merely by way of example, and the invention may take other forms within the scope of the appended claims.

What is claimed is:

5. 1. A prefabricated door and door frame assembly comprising, a two-part frame including front and back sections, each section having spaced jambs and a lintel and face panels on said jambs and lintels, a door hingedly mounted on one jamb of one of said sections, and jack members carried by the jambs of one of said sections and 10 movable outwardly thereof to contact the sides of a rough door opening and initially plumb that section in a rough door opening and hold said section in place during the installation of the other section and the permanent 15 securing of both sections in place.

2. In a prefabricated door and door frame assembly as claimed in claim 1, means projecting from the inner edges of the jambs and lintel of one of said sections, and the inner edges of the jambs and lintel of the other of said 20 sections having grooves to receive the said projecting means for aligning the respective jambs and lintels of the two sections.

3. In a prefabricated door and door frame assembly as claimed in claim 1, said jacks comprising a hollow threaded hub portion fixed to the jambs of said one section and a screw member having a bearing head threaded into said hub.

4. In a prefabricated door and frame assembly as claimed in claim 1, said jacks comprising a hollow threaded hub portion and a screw member having a bearing head threaded into said hub, a flange encircling said hub, said flange being partially imbedded in the inner edges of the jambs of the frame section carrying said jacks and protruding therefrom, the inner edges of the 35 jambs of said other frame section having grooves to receive the projecting portions of said jack flanges to align the respective jambs of said frame sections.

5. A prefabricated door and door frame assembly comprising, a two-part frame including front and back sections, each section having spaced jambs and a lintel and face panels on said jambs and lintels, a door hingedly mounted on one jamb of one of said sections, and jack members carried by the jambs of one of said sections, said jacks having hollow threaded hub portions attached to the jambs with their axes lying transversely of the jamb, 45 and a screw member having a bearing head threadedly engaged in said hub with the bearing head exteriorly of the frame, whereby movement of the screw members of said jacks will seat the bearing heads against the sides of a rough door opening to initially plumb the section carrying said jacks in the opening and hold said section in position during the installation of the other said section and the permanent securing of both sections in place.

6. In a prefabricated door and door frame assembly as claimed in claim 1, means projecting from the inner edges of the jambs of one of said sections in the plane of said jambs, and the inner edges of the jambs of said other frame section having grooves to receive the projecting means to align the respective jambs of the two frame sections.

7. A prefabricated door and door frame assembly comprising, a two-part frame including front and back sections, each section having spaced jambs and a lintel and face panels on said jambs and lintels, a door hingedly mounted on one of the jambs of one of said sections, said jambs of one of said sections having grooves in their inner edges extending the lengths of the edges, a tongue fixed in each of said grooves, and projecting beyond the edges of said jambs, jacks carried by said tongues extendible transversely of said tongues, and said jambs of said other frame section having their inner edges grooved to receive said tongues to align the respective jambs of the two frame sections.

8. In a prefabricated door and door frame assembly as claimed in claim 7, said jacks having a hub portion pro-

jecting through said tongue, and a flange encircling said hub portion to abut the tongue and be secured thereto.

9. In a prefabricated door and door frame assembly as claimed in claim 7, means to hold the bottoms of the jambs of said first section in spaced relation during installation.
